UNITED STATES PATENT OFFICE.

CHARLES W. REINOEHL AND BENT L. WEAVER, OF STEELTON, PENNSYLVANIA.

REVERSIBLE-GUARD GUARD-RAIL.

No. 912,618.

Specification of Letters Patent.

Patented Feb. 16, 1909.

Application filed February 4, 1908. Serial No. 414,261.

To all whom it may concern:

Be it known that we, CHARLES W. REINOEHL and BENT L. WEAVER, citizens of the United States, and residents of Steelton, 5 Dauphin county, State of Pennsylvania, have invented certain new and useful Improvements in Reversible-Guard Guard-Rails, of which the following is a full, clear, and exact description, reference being had to 10 the accompanying drawings, of which—

Figure 1 is a plan view of a stock rail showing our guard rail attachment applied thereto. Fig. 2 is a section on the line $x-x$, Fig. 1.

15 The object of this invention is to provide a guard rail attachment for an ordinary T-rail or the like, which may be readily renewed, and when worn, may be reversed to bring an unworn portion thereof into position to constitute a guard.

A further object is to provide means for adjusting said guard rail attachment with relation to the stock rail, to take up wear.

The invention consists in providing a 25 guard rail or bar of metal suitably shaped on its upper and lower surfaces, to constitute a guard, when either surface is uppermost and the said bar secured in place to the stock rail.

30 The invention further consists in certain details hereinafter pointed out.

In the drawings, 1 is a main or stock rail of the usual T-rail type. Fitted to the under side of the head and the inner side of the web 35 of the stock rail 1, is a bar or guard rail 2, having a body portion 3 whose upper and lower surfaces are of corresponding shape, each constituting, when uppermost, a guard rail gutter floor 4, and said body having extending oppositely therefrom, limbs 5 approximately a distance equivalent to that 40 from said floor 4 to the plane of the top of the stock rail head, each of said limbs 5 constituting, when uppermost, a guard. This 45 bar or piece 2 is suitably secured to the stock rail, in this instance in the following manner:—The upwardly extending limb or end portion 6 of a clamp strap 7 engages the outer face of the bar 2. In this instance 50 the end portion 6 is provided with inner converging surfaces and the outer faces of the limbs 5 of the guard rail converge and are engaged by the converging surfaces of the end portion 6 of the clamp strap. The horizontal member 8 of the clamp strap 7 passes 55 under and supports the lower surface of the

then downwardly extending one of the limbs 5, and also the stock rail 1, its outer end passing beyond said stock rail and being turned upwardly and slightly inwardly to 20 constitute a limb 9.

Fitted to the outer edge of the stock rail is a block 10, and between said block 10 and the inner surface of said limb, the end portion 9 of the clamping strap, a suitable wedge or other fastening means 11, is inserted, and driven home, thus securely clamping the stock rail 1 and the guard rail forming bar 2 together. In this instance, we have interposed between the bar 2 and the stock rail 1, shims 12. As the inner surface of the guard rail portion 5 wears, this wear may be taken up by removing one or more of the shims 12, and again securing the clamps in place; the wedges 11 being driven to such extent as to 75 firmly secure the parts together with the guard rail bar 3 in its new position of adjustment. When, for any reason, it is desired to reverse the bar 2 so as to bring the lower guard rail forming portion 5 there- 80 of into the upper position, all that is necessary is to remove the clamps, reverse said bar 2, and replace the clamps.

We remark that our guard rail attachment may be readily rolled from suitable 85 metal, and by making the body portion 3 thereof with the recess 13 shown in Fig. 2, there is considerable saving of metal.

Having thus described our invention, we claim as new and desire to secure by Letters 90 Patent:—

1. A guard rail structure comprising a stock rail, a clamp strap having the central bottom portion and the upwardly extending end portions, a reversible guard rail having 95 the central body portion and the respective upwardly and downwardly extending guard forming limbs, said guard rail being interposed between said stock rail and one end portion of the clamp strap, and means interposed between the other end portion of the clamp strap and the stock rail for clamping the parts together.

2. A guard rail structure comprising a stock rail, a clamp strap having the central 105 bottom portion and the upwardly extending end portion, a reversible guard rail having the central body portion and the respective upwardly and downwardly extending guard forming limbs, said guard rail being interposed between said stock rail and one end portion of the clamp strap, and a block and 110

a wedge interposed between the other end portion of the clamp strap and the stock rail for securing the parts together.

3. A guard rail structure comprising a stock rail, a clamp strap having the central bottom portion and the upwardly extending end portions, one of said end portions being provided with inner converging surfaces, a reversible guard rail having the central body portion extending beneath the head of the stock rail and having the respective upwardly and downwardly extending guard forming limbs having outer converging faces engaging the converging faces of one end portion of the clamp strap, and means interposed between the other end portion of the clamp strap and the stock rail for clamping the parts together.

4. A guard rail structure comprising a stock rail, a clamp strap having the central bottom portion and the upwardly extending end portions, a reversible guard rail having the central body portion and the respective upwardly and downwardly extending guard forming limbs, said guard rail being interposed between said stock rail and one end portion of the clamp strap, means interposed between the other end portion of the clamp strap and the stock rail for clamping the parts together, and a removable shim interposed between the guard rail and the stock rail.

5. A guard rail structure comprising a

stock rail, a clamp strap having the central bottom portion and the upwardly extending end portions, a reversible guard rail having the central body portion and the respective upwardly and downwardly extending guard forming limbs, said guard rail being interposed between said stock rail and one end portion of the clamp strap, a block and a wedge interposed between the other end portion of the clamp strap and the stock rail for securing the parts together, and a removable shim interposed between the guard rail and the stock rail.

6. A guard rail structure comprising the stock rail, the bar having the body portion fitted to the under side of the head and the web of said stock rail, and provided with the respective upwardly and downwardly extending guard-forming limbs, together with the clamp strap having the upwardly extending limb engaging said bar, the horizontal member passing beneath the bar and stock rail and supporting said bar, and means for securing the outer end of said clamp strap to the stock rail, substantially as set forth.

In testimony whereof, we have hereunto affixed our signatures.

CHARLES W. REINOEHL.
